EXPANSIBLE MOLDING CORE

Karl P. Billner, Philadelphia, Pa., assignor to
Vacuum Concrete, Inc., a corporation of Pennsylvania

Application March 9, 1949, Serial No. 80,478

5 Claims. (Cl. 25—128)

1

This invention relates to a form primarily intended for use in molding concrete bodies.

The production of hollow concrete bodies such as tunnel linings, pipes, caissons, and columns, for example, has customarily required the use of composite internal forms which must be dismantled after each casting operation and then reassembled for the next. Inflatable forms of known types have not been suitable for such purposes, since they would not produce the accuracy and finish required for many structures of these types.

In accordance with the present invention there is provided a unitary expansible internal form for hollow concrete bodies comprising a relatively rigid core, a relatively yieldable resilient tubular metal shell having a relatively high yield point surrounding the core, the shell having its ends secured to the core in fluid tight relationship, and means defining a passage for introducing fluid under pressure between the core and shell to expand the shell.

At least one end of the shell is preferably reduced to facilitate removal of the form from the molded body after the latter has become self supporting. In a great many applications, the shell will be flared at one end so that the effect of pressure will impose forces thereon longitudinally as well as radially to increase its expansion and contraction corresponding to a given pressure differential. The core itself is preferably of tubular metal construction and may be internally reinforced by reinforcing annuli secured within it in spaced relationship.

The fluid passage may penetrate the core at a convenient point to admit gaseous or liquid material under pressure for expanding the shell and/or to permit withdrawal of gaseous or liquid material from the chamber defined between the core and shell.

For many of the uses contemplated, the shell will have a circular cross section and in most such cases, it will be substantially cylindrical throughout a substantial portion of its length. The introduction of fluid under pressure into the chamber between the core and shell will produce expansion of the relatively yieldable shell, the extent of which can approach its elastic limit. Concrete is poured about the form in its expanded condition, and as soon as the plastic mass becomes solidified and self supporting, the pressure will be removed and the shell will contract due to its inherent elasticity, permitting its ready withdrawal from the cast body. Contraction of the shell can be increased by creating a reduced

2

pressure within the chamber through the use of a vacuum pump.

A more complete understanding of the invention will follow from a detailed description of the accompanying drawings wherein:

Fig. 1 is a sectional elevation of an internal form for molding tubular concrete bodies;

Fig. 2 is a sectional elevation taken along line 2—2 of Fig. 1;

Fig. 3 is an elevation partially in section depicting a form suitable for molding tunnel linings; and

Fig. 4 is a sectional elevation taken along line 4—4 of Fig. 3.

With particular reference to the form depicted in Figs. 1 and 2, a relatively rigid tubular core 10 which is substantially cylindrical throughout the major portion of its length, has one of its ends 12 outwardly flared by virtue of its diverging internal wall 14 and external wall 16. Surrounding the core 10, there is provided a coaxial and coextensive tubular metal shell 18 having a reduced convergent end 20 secured to the core by a welded joint 22, and a divergent flaring end 24 secured to the flared end of the core by a welded joint 26.

The envelope 28 defined by the interconnected core and shell provides a chamber whose internal pressure can be modified by introducing or withdrawing fluid. A passage for such fluid is defined by means of a nipple 30 penetrating the core at a suitable point, for communication with external pumps, as through a manifold 32 having branches 34 and 36 provided with stop valves 38 and 40 respectively.

The internal form shown in Figs. 1 and 2 can be utilized in various ways. For example, assuming that the internal form has been positioned with respect to a suitable external form, the valve 38 can be opened for communication with a vacuum pump, the valve 40 being closed, whereupon the shell 18 will tend to conform to the external wall 16 of the core. A plastic concrete mix may then be deposited about the internal form and suitably compacted by vibration, whereupon the valve 38 can be closed and the valve 40 opened to admit a suitable fluid, such as water, under pressure from a pump through the branch pipe 36, open valve 40, manifold 32 and nipple 30, into the envelope defined by the interconnected core and shell. The shell 18 will then be extended radially with respect to its relatively rigid core 10 to compact the concrete to a greater extent. Then, after the concrete has become self-supporting, the valve 40 can be

closed, the valve 38 opened to again contract the shell, and the form as an entirety can be withdrawn from the molded product with facility.

It is contemplated that the resilient metal shell 18 have a minimum yield point of fifty thousand pounds per square inch and a stiffness far in excess of that obtainable with rubber bags of the types that have been proposed for inflatable forms in the past. Assuming that the internal cylindrical diameter of the shell is thirty-six inches and the maximum internal diameter of the flared portion is forty-eight inches, and further assuming that a subatmospheric pressure of twenty-five inches of mercury is provided through the nipple 30, the pull tending to flatten the shell will approximate five tons. This will follow from the relationship:

$$P = \frac{12.5\pi}{4} (D^2 - d^2)$$

where P is the pull in pounds, D is the maximum diameter of the flared portion, d is the diameter of the cylindrical portion, and the value 12.5 is the pressure in pounds per square inch corresponding to a vacuum of twenty-five inches of mercury.

In a similar manner, for a tunnel having a diameter of twenty feet, where the diameter of the flared portion of the shell has a maximum measurement of twenty-one feet, the pull will be computed as approximately 29.5 tons.

Another manner in which the form can be employed is by introducing fluid under pressure through the branch pipe 36 and valve 40, the valve 38 being closed, prior to pouring the concrete, thereby extending the shell to a desired degree, then pouring the concrete, and after the material has become sufficiently hardened and self-supporting, the valve 40 can be closed, the valve 38 opened, and the effect of subatmospheric pressure utilized to contract the shell from its contact with the molded material, whereupon the form as an entirety can be removed as a unit.

Somewhat similar apparatus has been depicted in Figs. 3 and 4 as applied to the forming of a tunnel lining. An external form 42 may be defined by a suitable excavation, the left end of the internal form being supported upon previously formed and hardened concrete 44. The right end of the form will be supported in a suitable manner, substantially centered within the outer form 42, whereupon concrete in a plastic condition can be poured between the internal and external forms.

In this case, the shell 18 has been depicted as reduced at both ends and welded to the ends of the core 10. Here again, the shell is composed of resilient metal, preferably having a yield point in excess of fifty thousand pounds per square inch, yet relatively yieldable as compared with its core 10. The wall thickness, and accordingly the weight, of the core 10 can be somewhat reduced by using internal reinforcements in the form of spaced annuli 46 welded to the internal wall 14 of the core at suitable intervals. Here again, the core is penetrated by a nipple 30 which is connected through a manifold 32 with a branch pipe 34 leading to a vacuum pump and provided with a valve 38, and a branch pipe 36 leading to a pressure pump and provided with a valve 40.

The operation of the apparatus depicted in Figs. 3 and 4 may be similar to that described with reference to Figs. 1 and 2. In other words, the shell may be contracted before the concrete

is poured, then expanded to compact the concrete, and then again contracted to permit the unitary form to be shifted to the right to a new position after the concrete has become sufficiently hard and self supporting. Alternatively, the shell may be expanded initially, the concrete then poured, and the shell then contracted for movement to its new position.

Whereas only two forms of the invention have been illustrated, variations will occur to those skilled in the art, just as they have been recognized already by the present inventor. Accordingly, the invention should not be restricted to the examples shown beyond the scope of the appended claims.

I claim:

1. An expansible internal form for hollow concrete bodies comprising a relatively rigid core, a relatively yieldable resilient tubular metal shell 20 surrounding said core, said shell having two longitudinally spaced ends secured to said core in fluid tight relationship defining a chamber, said shell having a divergent portion adapted for exposure to atmospheric pressure adjacent one of said ends, and means defining a passage communicating with said chamber for modifying the fluid pressure between said core and shell to displace portions of said shell radially and longitudinally relative to said core.
2. An expansible internal form for hollow concrete bodies comprising a relatively rigid core, a relatively yieldable resilient tubular metal shell surrounding said core, said shell having two longitudinally spaced ends secured to said core in fluid tight relationship defining a chamber, at least one of said ends being reduced, at least one of said ends being adapted for exposure to atmospheric pressure externally thereof, and means defining a passage communicating with said chamber for modifying the fluid pressure between said core and shell to extend a portion of said shell longitudinally relative to said core as a function of the differential between said fluid pressure and atmospheric pressure.
3. An expansible internal form for hollow concrete bodies comprising a relatively rigid tubular core, a relatively yieldable resilient tubular metal shell surrounding said core, said shell having two longitudinally spaced ends secured to said core in fluid tight relationship defining a chamber, said shell and core flaring towards one of said ends, at least one of said ends being adapted for exposure to atmospheric pressure externally thereof during a molding operation, and means defining a passage communicating with said chamber for introducing fluid under pressure between said core and shell to expand said shell relative to said core.
4. An expansible internal form for hollow concrete bodies comprising a relatively rigid tubular core, a relatively yieldable resilient tubular metal shell surrounding said core, said shell having two longitudinally spaced ends secured to said core in fluid tight relationship defining a chamber, said shell having a divergent wall adjacent one of said ends for exposure to unequal fluid pressures on opposite surfaces thereof, reinforcing members secured within said core, and means defining a passage communicating with said chamber for introducing fluid under pressure between said core and shell into contact with one of said surfaces to expand said shell.
5. An expansible internal form for hollow concrete bodies comprising a relatively rigid core, a relatively yieldable resilient tubular metal shell

surrounding said core, said shell having two longitudinally spaced ends secured to said core in fluid tight relationship defining a chamber, said shell having a divergent wall adjacent one of said ends for exposure to unequal fluid pressures on opposite surfaces thereof, spaced reinforcing annuli secured within said core, and means defining a passage communicating with said chamber for introducing fluid under pressure between said core and shell into contact with one of said surfaces to expand said shell.
